UNITED STATES PATENT OFFICE.

EDWARD BROWN, OF PHILADELPHIA, PENNSYLVANIA.

HOT-BLAST PYROMETER.

SPECIFICATION forming part of Letters Patent No. 247,240, dated September 20, 1881.

Application filed March 19, 1881. (No model.)

To all whom it may concern:

Be it known that I, EDWARD BROWN, of 311 Walnut Street, Philadelphia, Pennsylvania, have invented a new and useful Hot-Blast 5 Pyrometer-Fitting, of which the following is a specification.

My invention consists in a branch pipe or nozzle fitted to the hot-blast main and open to the hot-blast. Upon this pipe are two valves, 10 one at the bottom, the other at the top. The lower one is connected with the cold-blast main pipe, the upper one opens to the atmosphere.

These valves are adjustable in relation to each other, so that the hot and cold blast may 15 be mixed in certain definite proportions. The cold blast or air passes through a water-tank to maintain the blast at a certain fixed temperature.

The figure is a vertical section through the 20 apparatus, the valves and rod being shown in elevation.

A is the hot-blast main, lined with fire-brick.

B is a branch pipe closed at the top end, and 25 secured at its lower end to the hot-blast main by the saddle C. This branch pipe has an outside case, b', and is open at the bottom to the hot-blast. The lower valve, D, communicates by pipe d' with the cold-blast main from the engine. The upper valve, E, discharges the 30 mixed hot and cold blast into the atmosphere.

H is the ordinary Gauntlet pyrometer, having its usual dial and a tubular stem, h', enclosing a rod of a different metal. The handles e' and d' of the valves are jointed with 35 pins to the upright rod K. The lower pin has on it a thumb-screw, d'', by which it can be adjusted in the slot k'. The air from the atmosphere or from the cold-blast main passes through a coil, M, in the water-tank N, by which the 40 cold air may be kept at a fixed temperature when indicating the temperature of the hot-blast.

Adjust the valves in this way: Start the pyrometer at 0 Fahrenheit before inserting it in 45 the branch B. Let the hot-blast be at some temperature which will not injure the stem h'; open the valve E wide to the stop e'', and we will assume the pyrometer shows 900° actual

temperature of blast; then open valve D and admit cold-blast until the pyrometer shows 600°, 50 or one-third less than the true temperature, and tighten the thumb-screw d' in its position in the slot k'. The instrument is now ready for use. The handle S being raised, the pointer of the pyrometer will always show two-thirds of 55 the correct temperature. In place of the pyrometer H, my portable pyrometer may be used at the outlet of valve E. This plan obviates any error from a varying pressure of the hot-blast, as the pressure of the hot and cold blast 60 remains relatively the same. It also obviates error from the varying temperature of the atmosphere.

I claim—

1. The combination, in a hot-blast pyrometer-fitting, of a hot-blast main, a branch pipe secured thereto, a valve connecting with the interior of the branch pipe and opening to the atmosphere, a second valve, also communicating with the interior of the branch pipe and 70 connecting with the cold-air main, and means for simultaneously operating both valves and adjusting the second valve, whereby the admission of cold air and the proportions of hot and cold air are accurately adjusted, substantially 75 as and for the purposes set forth.

2. In a hot-blast pyrometer-fitting, a hot-blast main, a branch pipe secured thereto, a valve connecting with the interior of the branch pipe and opening to the atmosphere, and a 80 second valve, also communicating with the interior of the branch pipe and connecting with the cold-air main, combined with means for simultaneously operating both valves and adjusting the second valve, and with a water-tank, through which the cold-air pipe passes, 85 whereby both the quantity of the cold air admitted, the proportions of the hot and cold air mixed, and the temperature of the cold air are adjusted and regulated, substantially as and 90 for the purposes set forth.

EDWARD BROWN.
